DISPLAY BRACKET

John Lowe, Jr., Winfield, Kans.

Application March 22, 1934, Serial No. 716,900

3 Claims. (Cl. 248—242)

This invention relates to display brackets; and, more particularly, one designed for advertising purposes.

The principal object of the invention is to provide a shelf to hold merchandise, and which is adjustable so as to most advantageously display the same.

Other structure is designed to carry advertising matter and price information.

Another object of the invention is to devise a compact, efficient wall bracket, capable of adjustably displaying merchandise in the most efficient manner and utilizing this structure for price and advertising matter.

Other objects of the invention will be disclosed in the specification and claims forming a part of this application.

In the drawing:

Figure 1 is a front elevation of the display bracket;

Figure 2 is a side elevation, partly in section; Figure 3 is an exploded view of some of the elements in perspective;

Figure 4 is a vertical section taken on line 4—4 of Figure 1;

Figure 5 is a detailed vertical section taken on the line 5—5 of Figure 2;

Figure 6 is a modified form of the invention showing the advertising display on front and sides instead of only in front as shown in Figure 1; and

Figure 7 is a horizontal section taken on line 7—7 of Figure 6;

Referring to the drawing, in which similar parts are designated with like numerals:

Numerals 8 designates an arm having screw holes 9 in a vertical leg portion 10. Extending from the vertical leg portion 10 at a substantial right angle is an elbow 11 having a pivoted ear 12 adapted to receive a bifurcated pivotal joint 13 with a bolt 14 extending therethrough and held in place by a wing nut 15 supported by the joint 13 is a circular shelf 16 adapted to receive merchandise to be displayed. The elbow 11 and the bottom portion of the leg 10 have angular faces cut in substantially the same plane to receive a brace 17 which is secured by screws 18 and forming the hypotenuse of a substantial triangle.

Supported by the brace 17, as shown in Figures 1 and 2, is a display board 19 having channels 20 formed around the outer edges along the sides and bottom to receive display advertising, in the form of a sheet of material, such as cardboard. At the extreme bottom of the display board 19 a space is formed to receive a price placard 22, projections 23 extending out from the edges of the channels 20 to receive the placard, the channels 20 extending beneath said projections 23.

Formed around the sides of the top 24 of the shelf 16 are grooves 25 adapted to receive display cards, or other advertising material.

In the modified form as shown in Figure 6, the display board 19 extends around the sides and front instead of only on the front, and is supported on the sides by the leg 10 and elbow 11 which are flat sided.

As actually used, the arm 8 will be screwed into a wall or support and the circular shelf 16 tilted to the desired position and the wing nut 15 tightened to hold the same in position. Merchandise is then placed on the circular shelf and an announcement in connection with the same, such as price, placed by way of cards in the grooves formed in the sides of the shelf. Other display indicia or announcements are placed in the channel formed in the display board 19, the display board further serving as a brace and support for the shelf, arm, and elbow. Under this arrangement, a very unique, strong, and compact device is provided which serves a number of purposes in connection with a display bracket.

Numerous variations may doubtless be devised by persons skilled in the art without departing from the principles of my invention. I, therefore, desire no limitations to be imposed on my invention, except such as are indicated in the appended claims.

What I claim is:

1. A display device comprising a base adapted to be secured to a wall, a bracket extending laterally from said base near one end thereof, a brace secured to the outer ends of said bracket and base and formed as a plate having its opposite edges grooved to receive interchangeable advertising signs, and a platform fixed to said bracket to support objects intended to be advertised by said signs.

2. A display device comprising a base adapted to be secured to a wall, a bracket extending laterally from said base near one end thereof, a brace secured to the outer end of said bracket and base and formed as a plate having its opposite edges grooved to receive interchangeable advertising signs, a platform fixed to said bracket to support objects intended to be advertised by said signs, said platform having an apron depending from its periphery and channeled to receive additional interchangeable advertising matter relating to said objects.

3. A display device comprising a base adapted to be secured to a wall, a bracket extending laterally from said base near one end thereof, a brace secured to the outer ends of said bracket and base and formed as a plate having means to support interchangeable advertising signs, and a platform fixed to said bracket to support objects intended to be advertised by said signs.

JOHN LOWE, JR. 60
